To whom it may concern:

Be it known that we, William A. Lieberman and Jack Warren Thomsen, citizens of the United States, residing at Chicago, in the county of Cook and State of Illinois, have invented a new, original, and ornamental Design for a Film Slide Viewer, of which the following is a specification, reference being had to the accompanying drawing, forming part thereof.

Figure 1 is a front elevational view of a film slide viewer, showing our new design;

Figure 2 is a side elevational view of a film slide viewer; and

Figure 3 is a top plan view thereof.

We claim:

The ornamental design for a film slide viewer, as shown.

WILLIAM A. LIEBERMAN.
JACK WARREN THOMSEN.
